J. H. RATTA

VENTILATOR

Filed April 21, 1924

J. H. Ratta,
Inventor

By *Parsons and Brinckerhoff*
Attorneys

UNITED STATES PATENT OFFICE.

JOSEPH H. RATTA, OF HONOLULU, TERRITORY OF HAWAII.

VENTILATOR.

Application filed April 21, 1924. Serial No. 707,929.

To all whom it may concern:

Be it known that I, JOSEPH H. RATTA, a citizen of the United States, residing at Honolulu, in the county of Honolulu and 5 Territory of Hawaii, have invented certain new and useful Improvements in a Ventilator, of which the following is a specification.

This invention relates to new and useful 10 improvements in ventilators which are principally adapted for use in connection with the port holes provided in the staterooms of a ship.

One of the important objects of the present 15 invention is to provide an automatic means for closing the port hole when the waves or water strike a portion of my ventilator thereby preventing any possibility of the water from entering the staterooms 20 through the port holes, means being further provided for automatically returning the ventilator to its normal position whereby the port hole is again opened so as to admit air therethrough.

25 A further object of the invention is to provide a ventilator of the above mentioned character, which may be easily and conveniently placed in position in the port holes of a ship without materially altering the 30 construction of the ship, the ventilator being at all times positive in its operation.

35 A further object of the invention is to provide a ventilator of the above mentioned character, which is simple in construction, inexpensive, strong and durable and furthermore adapted for the purposes 40 for which it is designated.

45 Other objects and advantages of this invention will become apparent during the course of the following description.

In the accompanying drawing forming a part of the specification, and in which like numerals designate like parts throughout the same,

45 Figure 1 is a front elevation of my improved ventilator showing the same in position,

Figure 2 is a longitudinal section therethrough, and

50 Figure 3 is a transverse section taken approximately on line 3—3 of Figure 1.

In the drawing wherein for the purpose of illustration is shown the preferred embodiment of my invention, the numeral 1 designates generally my ventilator which

comprises the elongated casing 2, the same being substantially cylindrical, the forward portion of the casing is cut away for its greater length as more clearly shown in Figure 2 of the drawing to provide a substantially semi-circular outwardly projecting portion 3. The inner end or base portion 4 of the casing is adapted to fit snugly in the port hole A of a vessel B in the manner clearly shown so that the forward end 60 of the casing will extend beyond the outer face of the side of the vessel. For permitting the ventilator to be placed in position in the port hole A and to further prevent the displacement therefrom, I provide 65 the handle 5, the ends of which are secured to the inner end of the casing and are flared outwardly as shown at 6 in the drawing to engage the inner side of the vessel adjacent 70 the port hole.

Extending forwardly from the semi-circular portion 3 of the casing 2 are the angular brackets 7, the forward ends of which are bent downwardly as shown at 8 to provide stops, the brackets 7 forming a guide 75 means for the elongated plate 9 which is curved transversely. The plate 9 is adapted to be supported between the brackets 7 in the manner clearly illustrated in the drawing and for the purpose of normally holding the same in a forward position, I provide the coil springs 10, the rear portions 80 of which are supported in suitable brackets 11 mounted on the inner face of the semi-circular portion 3 of the casing. The bent 85 portions 8 provided on the forward ends of the brackets 7 provide a means for limiting the forward movement of the plate 9 and the plate 9 is adapted for lateral movement 90 on the brackets 7 for the purpose to be hereinafter more fully described. Suitable 95 bracing means such as is shown at 12 is adapted to extend across the bent down portions 8 of the brackets 7 and secured thereto in any well known manner and the ends of braces 12 are secured to the top and bottom of the semi-circular portion 3 of the casing 2 and provide a means for rigidly 100 supporting the forward ends of the brackets 7 in the manner clearly illustrated.

Extending transversely through the central portion of the inner end of the casing 2 is the rod 13 and pivotally supported thereon is the closure plate or damper 14. The damper is adapted to conform to the con- 105

tour of the inner portion of the casing and in the present invention is shown as being circular to conform to the cylindrical conformation of the base portion 4 of the casing. The closure or damper 14 is adapted to cooperate with the spaced baffle flanges 15 and 16 respectively which are arranged on the inner end of the casing in the manner shown in Figure 1 of the drawing so that the outer edges of the closure will engage the flanges when in a closed position in the manner as will be presently described.

Pivottally connected to the damper 14 is the link 17 the latter being pivottally connected to the closure or damper by means of the bracket 18 and this link is twisted intermediate its ends as shown more clearly in the drawing and the opposite end of the link is connected to the outer end of the longer arm 20 of the bell crank lever 19. The bell crank lever 19 is pivoted at 20 in the bracket 21 supported by the rear wall of the casing and the outer end of the shorter arm of the bell crank lever is pivottally connected to the inner end of the plate 9 as shown at 22 in the drawing. The connection of the character above described provides a means whereby the damper will operate simultaneously with the operation of the plate 9.

30 Normally the parts are arranged as shown in the drawing wherein the springs 10 normally keep the plate 9 in a forward position and the damper 14 is in an open position and out of engagement with the flanges 15 and 16 so that air may circulate around the inner walls of the casing and will pass through the inner end of the same into the port hole and stateroom.

It is of course to be understood that the 40 forward portion or open part of the casing is disposed in the same direction in which the ship is traveling so as to cause the air currents to be deflected by the outwardly projecting portion of the casing and be directed into the state room in the port hole of which is mounted the ventilator. To prevent water or the waves from entering the stateroom through the port hole and through the ventilator, it will be readily seen that when 50 the waves strike the plate 9 the same will move rearward against the tension of the springs 10 simultaneously swinging the damper 14 on its pivot 13 through the connection of the bell crank lever and the link 55 above described so that the damper will engage the flanges 15 and 16 and will be closed thus preventing the possibility of any water from entering through the port hole and into the stateroom. After the water or 60 waves have receded, the springs 10 will return the plate 9 and the damper 14 connected thereto to their normal positions whereby air will again be admitted to the stateroom. For the purpose of permitting water which 65 may accumulate in the base portion of the

casing to be discharged, I provide the opening 23.

It will thus be seen from the foregoing description, that a ventilator for use in connection with the port hole of a vessel has been provided which will automatically close the port hole when the waves or water come in contact therewith and will automatically reopen the port hole when the waves have receded. The simplicity with which my device is constructed enables the same to be easily and readily placed in position on a vessel and will at all times be supported in an operative position. A device of this character may be turned depending upon the direction in which the ship travels so that the front or forward face of the casing which is cut away will be disposed in the direction of travel which the ship pursues. A device of the character described may be further manufactured at a very low cost and will be strong and durable.

While I have shown the preferred embodiment of my invention, it is to be understood that various changes in the size, shape and arrangement of parts may be resorted to without departing from the spirit of the invention and the scope of the appended claims.

Having thus described my invention, what I claim is:

1. A ventilator comprising an elongated casing having its forward portion cut away for its greater length, the inner end of said casing being adapted to be supported in the port hole of a ship, a plate supported in said casing and adapted for lateral movement therein, a closure for the inner end of said casing, connecting means between said plate and said closure, said closure being normally in an open position when said plate is in the forward part of said casing, and in a closed position when said plate is moved rearwardly in the casing.

2. A ventilator comprising an elongated casing having its forward portion cut away for its greater length, the inner end of said casing being adapted to be supported in the port hole of a ship, a plate supported in said casing and adapted for lateral movement therein, a closure for the inner end of said casing, connecting means between said plate and said closure, said closure being normally in an open position when said plate is in the forward part of said casing, and in a closed position when said plate is moved rearwardly in the casing, and resilient means for returning and holding the plate and closure to their normal positions.

3. A ventilator comprising an elongated casing having its forward portion cut away for its greater length, the inner end of said casing being adapted to be supported in the port hole of a ship, a plate supported in said casing, guide means for said plate,

5 said plate adapted for lateral movement in said guides, a closure for the inner end of said casing, connecting means between said plate and said closure, said closure being normally in an open position when said plate is in the forward part of the casing, and in a closed position when said plate is moved rearwardly, and coil springs disposed between the rear wall of the casing 10 and said plate for returning and holding the plate and closure connected to their normal positions.

4. A ventilator comprising an elongated casing having its forward portion open for 15 its greater length and providing an attaching base at its inner end for engagement in the port hole of a ship, a plate, angular guides supported in said casing, said plate adapted for lateral movement in said guide, 20 a closure for the inner end of said casing, flanges arranged in said inner end of the casing cooperating with said closure, connecting means between said plate and said closure, said closure normally in an open 25 position when the plate is in the forward part of the casing, and in a closed position when the plate is moved rearwardly, coil springs associated with said plate and said casing for normally holding the plate and closure 30 associated therewith in their normal posi-

tions, and means for limiting the forward movement of the plate in the casing.

5. A ventilator comprising an elongated casing having its front portion cut away for its greater length providing an attaching base at its inner end for mounting the same in the port hole of a ship, a plate supported in said casing and adapted for lateral movement therein, a closure pivotally supported in the inner end of the casing, flanges 40 formed on the inner wall of the inner end of the casing and adapted to cooperate with said closure, a bell crank lever pivotally supported in said casing adjacent the inner end thereof, a link pivotally connected to 45 said closure and to one end of said bell crank lever, the opposite end of said bell crank lever being connected to said plate, said closure being normally in an open position when the plate is in the forward portion of the casing, and in a closed position in engagement with the flanges when the plate is moved rearwardly, means for returning and holding the plate and closure to their 50 normal positions, and means for limiting the forward movement of the plate in the casing.

In testimony whereof I affix my signature.

JOSEPH H. RATTA.
